UNITED STATES PATENT OFFICE.

WILLIAM A. RUSSELL, OF YONKERS, NEW YORK.

FLOOR OR CEILING PLATE.

1,249,209.

Specification of Letters Patent.

Patented Dec. 4, 1917.

Application filed May 14, 1915. Serial No. 27,980.

To all whom it may concern:

Be it known that I, WILLIAM A. RUSSELL, a citizen of the United States, residing at Yonkers, county of Westchester, and State 5 of New York, have invented certain new and useful Improvements in Floor or Ceiling Plates, fully described and represented in the following specification and the accompanying drawings, forming a part of the 10 same.

This invention relates to certain improvements in floor or ceiling plates.

Floor and ceiling plates are now generally employed for surrounding radiator pipes, 15 water pipes or other pipes which are exposed in a room to conceal the hole in the floor or ceiling through which the pipe passes. To enable the plates to be positioned about the pipe, the plates are made in two parts 20 which, in the constructions now generally used, are either provided with two latches for locking the parts together, or pivotally united at one end and provided with a latch at the other. In such floor and ceiling plates 25 it is desirable and has become customary to form the plate so that the exposed surface of the plate is perfectly smooth and plane, such characteristics producing a neater and more finished appearance, the latches and 30 the pivot by which the two parts are secured together being concealed within the plate.

Where the plates are pivotally secured together at two of their ends, it frequently happens that through carelessness of workmen or for other reasons, the pivot point is 35 broken and the plate rendered useless, or it becomes sprung so that the surface of the plate at the pivotal point is not flush, one of the parts of the plate being raised above 40 the other, thus presenting an unsightly appearance and rendering the plate of no use.

It is the special object of the invention to provide an improved hinge construction in plates of the above mentioned class which 45 are secured together at one point by a swinging connection and secured at another point by a latch or other suitable locking device, the hinge being constructed so as to obviate breakage as far as possible and to stand firm 50 while the plate is being put in place and under conditions of use, so that the surface of the plate will be smooth and unbroken and give the desired neat appearance.

For a full understanding of the invention,

reference may be had to the accompanying 55 drawings, in which—

Figure 1 is a bottom view of a floor plate embodying the invention and showing the plate in position around a pipe;

Fig. 2 is a sectional view taken on line 60 2—2 of Fig. 1;

Figs. 3 and 4 are detail sectional views taken on lines 3—3 and 4—4, respectively, of Fig. 1 and

Fig. 5 is a bottom view of the plate in its 65 open position and ready to be placed about a pipe.

Referring now to these drawings, the improved plate comprises two members 1, 2, generally semicircular in shape and concave, 70 as shown in Fig. 2, this concave being provided to afford a space for the latch or other locking device and hinge construction hereinafter referred to, so that they are concealed. The members 1, 2 are interiorly 75 formed by turning or bending a piece of metal to form the exterior flange 4 and an interior pipe-encircling flange 5, and the metal when so bent is cut straight across, forming the two members 1, 2. The pipe 80 encircling flange 5 is at suitable intervals formed with downwardly extending prolongations or legs 6, which enter the hole around the pipe and frictionally engage the pipe wall, as shown in Fig. 2, and hold the 85 plate firmly in position.

The two members of the plate are adapted to be suitably locked together as by coöperating latch elements which may consist, as shown, of the spring tongue 7 carried by 90 the member 1, this tongue coöperating with the locking piece 8 which is carried by the member 2 and provided with a locking slot 9. The tongue 7 and the locking piece 8 are secured on the inner side of the members, and 95 in the particular construction shown are integral with supports 10, one for each member, which are secured to the members, preferably by welding thereto. These parts are thus concealed when the plate is in position. 100

The two plates 1, 2 are united at their other ends by a hinge, by which the plates are firmly secured together and at the same time may have a swinging movement with respect to each other, so that the plates can 105 be swung on the hinge to separate them to enable them to be placed in position about a pipe. While this hinge may vary some-

what in construction, it is so formed as to effectually prevent the hinge from being broken, or distorted, so that one of the plates will be raised above the other, as is frequently the case where a simple pivot is employed, as in certain prior constructions. This hinge will, furthermore, be of such character that the plates will have a swinging movement toward and away from each other, so that they may be separated sufficiently to permit them to be placed in position.

While the particular construction of the hinge may be somewhat varied, one of the plates 1, 2 will be provided with a hinge-plate or tongue which will engage a suitable member on the other plate with a swinging or sliding movement and will be held in firm engagement with such other member in both the open and closed positions of the plate, so as to provide in either of such positions of the plates, a strong, rigid structure.

In the best constructions, each of the plates 1, 2 will be provided with a hinge-plate or tongue 11, 12, these tongues being arranged to overlap each other for a substantial distance in the open position of the plates, as shown in Fig. 5, and for substantially their lengths, when the plates are closed. These tongues overlap and have a relative swinging or sliding movement with respect to each other, and to effect this the tongues are preferably formed in the shape of an arc, the curve of the arc being the reverse to that of the curve of the plates, as best shown in Fig. 5. These overlapping tongues are held superposed in rigid engagement with each other in any suitable manner. A convenient means for effecting this is that illustrated in which the tongue 12, which in the particular construction shown is the upper one, is formed with integral lugs 13, which are bent so as to extend under the lower tongue 11 on each side thereof. The plate 11 is formed with lugs 14 which are bent so as to extend over the upper plate 12. The plates are thus held firmly in engagement with each other. In addition to thus holding the tongues together, the lugs 13 form complementary stops, the lugs 13 engaging with the lugs 14, when the plates 1, 2 are swung open, and prevent the plates from swinging open too far and prevent the tongues from disengaging with each other. If desired, the tongues may be formed with a complementary bead and groove 15, 16, which act both to strengthen the tongues, which preferably are of light metal, and further act as a guide to cause the tongues to move truly in their arcs when they are given their sliding movement to open or close the plates.

These tongues 11, 12 may be secured on the inner surface of the plates 1, 2 in any suitable manner. To permit their free sliding move-

ment and to provide a space for the lugs 14, they are offset slightly from the plane of the inner surface of the plates and may be conveniently supported by being formed integral with bases 17, 18 secured to the inner surface of the respective plates 1, 2 in any suitable manner, and preferably by being electrically welded thereto.

By the construction described a very rigid structure is produced, because of the fact that the tongues are always in firm engagement with each other and are held against any substantial vertical yielding movement, with the result that the hinge is practically free from breakage, and, because of its rigidity, the two plates are held in their proper position and the desired smooth surface to the plates when they are in position is obtained.

While the invention has been described in its preferred form, it will be understood that certain variations in the form of the tongues, and in the means for holding them rigidly in position, may be made without departing from the claimed invention.

What is claimed is:

1. A floor or ceiling plate including a pair of semicircular plates formed with a pipe-encircling central opening, two adjacent ends of the plates being provided with coöperating locking devices and the other two ends of the plates being united by a pair of hinge members having a relative sliding movement and held in engagement with each other in both the open and closed positions of the plates.

2. A floor or ceiling plate including a pair of semicircular plates formed with a pipe-encircling central opening, two adjacent ends of the plates being provided with coöperating locking devices and the other two ends of the plates being united by a hinge including a pair of tongues overlapping each other in both the open and closed positions of the plates and having a sliding movement with respect to each other, and means for holding the tongues in engagement with each other.

3. A floor or ceiling plate including a pair of semicircular plates formed with a pipe-encircling central opening, two adjacent ends of the plates being provided with coöperating locking devices and the other two ends of the plates being united by a hinge including a pair of tongues overlapping each other in both the open and closed positions of the plates and having a sliding movement with respect to each other, and integral lugs on the tongues for holding them in engagement with each other.

4. A floor or ceiling plate including a pair of semicircular plates formed with a pipe-encircling central opening, two adjacent ends of the plates being provided with coöperating locking devices and the other

- two ends being united by a hinge including a pair of overlapping tongues rigidly secured to the inner surface of the plates and having integral lugs holding them in engagement with each other, said tongues being curved reversely to the curve of the plates and offset from the surface thereof and having a free sliding movement relatively to each other.
- 10 5. A floor or ceiling plate including a pair of plates formed with a pipe-encircling opening, two adjacent ends of the plates being provided with coöperating locking devices and the other two ends of the plates being united by a pair of hinge members having a relative sliding movement held in engagement with each other in both the open and closed positions of the plates and provided with means for guiding them during their movements.
- 15 6. A floor or ceiling plate including a pair of plates formed with a pipe-encircling opening, two adjacent ends of the plates being provided with coöperating locking devices and the other two ends of the plates being united by a hinge including a pair of tongues held in overlapped relation with each other in both the open and closed positions of the plates and having a sliding movement with respect to each other, the tongues being provided with complementary bead and groove for guiding them in their movements.
- 20 7. A floor or ceiling plate including a pair of plates formed with a pipe encircling

opening, two adjacent ends of the plates being provided with coöperating locking devices, bases secured to the inner faces of the plates at their other ends, said bases being each formed with a tongue held in overlapped relation with each other in both the open and closed position of the plates, and forming a hinge, said tongues having a sliding movement with respect to each other and provided with complementary bead and groove extending substantially the length of the tongues for guiding them in their movements and holding them securely in position.

8. A floor or ceiling plate including a pair of plates formed with a pipe encircling opening, two adjacent ends of the plates being provided with coöperating locking devices, bases secured to the inner faces of the plates at their other ends, said bases being each formed with a curved tongue held in overlapped relation with each other in both the open and closed position of the plates, and forming a hinge, said curved tongues having a sliding movement with respect to each other and provided with complementary curved bead and groove extending substantially the length of the curved tongues for guiding them in their movements and holding them securely in position.

In testimony whereof, I have hereunto set my hand.

WILLIAM A. RUSSELL.
